US00D982610S

(12) **United States Design Patent** (10) **Patent No.:** **US D982,610 S**
Chen et al. (45) **Date of Patent:** **** Apr. 4, 2023**

(54) **DISPLAY SCREEN OR PORTION THEREOF WITH GRAPHICAL USER INTERFACE FOR SURVEILLANCE SYSTEM**

(71) Applicant: **VIVOTEK INC.**, New Taipei (TW)

(72) Inventors: **Kuan-Hung Chen**, New Taipei (TW); **Kai-Sheng Chuang**, New Taipei (TW); **Chia-Chi Chang**, New Taipei (TW); **Yu-Fang Huang**, New Taipei (TW); **Kai-Ting Yu**, New Taipei (TW); **Wen-Chun Chen**, New Taipei (TW); **Shu-Jung Hsu**, New Taipei (TW); **Tsao-Wei Hung**, New Taipei (TW)

(73) Assignee: **VIVOTEK INC.**, New Taipei (TW)

(**) Term: **15 Years**

(21) Appl. No.: **29/785,235**

(22) Filed: **May 24, 2021**

(30) **Foreign Application Priority Data**

Dec. 4, 2020 (TW) 109306849

(57) **CLAIM**

The ornamental design for a display screen or portion thereof with graphical user interface for surveillance system, as shown and described.

DESCRIPTION

The FIGURE is a front view of a display screen or portion thereof with graphical user interface for surveillance system, showing our new design.

The outermost dot-dash broken lines in the FIGURE show a display screen or portion thereof and form no part of the claimed design. The other broken lines in the FIGURE show portions of the graphical user interface that form no part of the claimed design.

1 Claim, 1 Drawing Sheet
